UNITED STATES PATENT OFFICE.

CARL CLAUS, OF PHILADELPHIA, PENNSYLVANIA.

METALLIC TOTE-BOX.

1,331,862.

Specification of Letters Patent. Patented Feb. 24, 1920.

Application filed March 23, 1918. Serial No. 224,400.

To all whom it may concern:

Be it known that I, CARL CLAUS, a subject of the Emperor of Germany, having declared my intention of becoming a citizen of the United States, residing in Philadelphia, in the county of Philadelphia and State of Pennsylvania, have invented certain new and useful Improvements in Metallic Tote-Boxes, whereof the following is 10 a specification, reference being had to the accompanying drawings.

The invention relates more particularly to a box of the above character which is adapted to store heavy metallic parts, such as 15 bolts and the like.

An object of the invention is to provide 20 a tote box of the above character, having downwardly projecting supporting domes on which the box may be supported and moved about.

A further object of the invention is to provide a tote box having a top for closing in part or in whole the tote box, which top is provided with a series of recesses similarly disposed and shaped to the supporting domes, whereby one tote box may be placed on another; and held from movement thereon, so as to facilitate the stacking of the tote boxes.

30 A still further object of the invention is to provide a tote box having sides, ends and a top with an opening formed in part in the top and in part in the front end, which opening extends only partway across the 35 box, so as to provide supporting ledges at each side of the box to facilitate the stacking of the tote boxes one on another.

These and other objects will in part be 40 obvious and will in part be hereinafter more fully disclosed.

In the drawings which show by way of illustration one embodiment of the invention, Figure I, is a perspective view showing a tote box embodying my improvements.

45 Fig. II, is a vertical sectional view through two of my improved tote boxes, one supported by the other.

My improved tote box is preferably formed of metal and consists of a bottom portion 1, side portions 2, and 3, a front end portion 4, a rear end portion 5, and a top 6. The sides and ends and also the top and bottom as shown in the drawings, are all formed integral. The box is formed of sheet 55 metal and the meeting edges are joined by welding, thus forming an integral struc-

ture. It will be understood, of course, that the metal parts may be otherwise joined, the essential feature being that they shall be rigidly connected together so as to form 60 a single rigid structure. In the bottom are, as herein shown, six downwardly projecting domes indicated at 7. These domes are similarly shaped and so located as that they form a support for the tote box. My improved tote box is especially adapted for 65 storing heavy metal parts, such as metal bolts and the like, and, therefore, the tote box is very heavy and not easily handled. By these supporting domes, however, the 70 box may be readily slid in and out on shelving, or placed on a counter without injuring the parts which support the boxes. The front end 4, is cut away at its upper portion and the top 6, is cut away at the front 75 part thereof to form an opening 8. This opening being formed in part in the front end portion and in part in the top, gives ready access to the box for the filling of the same, and also gives ready access to the box 80 to reach the articles stored therein, when the boxes are placed one on another, as shown in Fig. II. The top is provided with recesses 9, which are shaped and disposed so as to receive the supporting domes 7, as 85 clearly shown in Fig. II, of the drawings. The extreme front edge of the top is bent back as at 10, to reinforce the metal edge at this portion of the top. The extreme upper edge of the front 4, is bent down as at 11, 90 to reinforce said front. The front of the box is also provided with a suitable label holder 12, and with a handle 13. The opening 8, does not extend entirely across the box, so that there are supporting ledges 14, 95 and 15, which extend to the front end of the box, and these supporting ledges are sustained respectively by the metal parts 16, and 17, at the front end of the box. When one box is placed on another, it rests in part 100 on the top 6, and in part on these supporting ledges 14, and 15. This makes a very firm and durable support, so that boxes with heavy metal parts stored therein may be placed one on top of the other. The sup- 105

porting domes extending into recesses prevent the boxes from sliding one on the other, as above noted.

It will be obvious that minor changes in the details of construction may be made 110 without departing from the spirit of the invention as set forth in the appended claims.

Having thus described my invention, I claim:

1. A metal tote box comprising sides, ends and bottom, said bottom having independently downwardly projecting domes formed from the metal thereof, said domes being similar in shape and size and disposed so as to form a supporting means for the tote box, said box having a top with recesses formed therein disposed so as to receive the supporting domes of a tote box placed on top thereof.
2. In a metal tote box comprising sides, ends, a bottom and a top, one of said ends and the adjacent portion of the top being cut away to form an opening for entrance to the box, said opening terminating short of the sides of the box so as to form at each side thereof supporting ledges extending to the front end of the box.
3. A metal tote box comprising sides, ends,

a bottom and a top formed of sheet metal united so as to provide an integral structure, said top at the forward end thereof and said front end at the upper portion thereof being cut away to form an opening in the box, such opening terminating short of the sides of the box, so as to form supporting ledges, said box having downwardly projecting domes formed in the bottom thereof, and correspondingly and similarly shaped recesses in the top thereof, so that the domes of one box may be nested within the recesses in another box.

In testimony whereof I have hereunto signed my name at Philadelphia, Pennsylvania, this twentieth day of March, 1918.

CARL CLAUS.
